Inventor:
S. Miller

UNITED STATES PATENT OFFICE.

S. MILLER, OF URBANA, OHIO.

IMPROVED EDGE-PLANE.

Specification forming part of Letters Patent No. 58,123, dated September 18, 1866.

To all whom it may concern:

Be it known that I, S. MILLER, of Urbana, in the county of Champaign and State of Ohio, have invented a new and useful Improvement on an Edge-Plane for Boots and Shoes; and I do hereby declare that the following is a full, clear, and exact description of the construction and operation of the same, reference being had to the annexed drawings, making a part of this specification, in which—

Figure 1 is a perspective view; Fig. 2, the detached face and bit of the machine.

The nature of my invention consists in hinging face A on pin D, and using thumb-screw C in conjunction with spring E, as shown by the dotted line, to elevate or depress face A immediately in front of the cutting-edge of bit B, thereby enabling me to expose the cutting-edge of bit B always evenly and securely at one operation, so as to cut deep or shallow, as the case may require.

To enable others skilled in the art to make and use my invention, I will proceed to describe its construction and operation.

I construct my plane-stock of any of the

hard metals, and of the form described, having a partition cast or riveted to the back of the stock, running obliquely from the cutting-edge of bit B, to form a throat for the discharge of shavings. Bit B, is supported between the stock and cap G in V-shaped grooves, whose edges have a corresponding shape. Near the lower edge of cap G is another V-shaped groove, which fits upon a projection in the stock of the same shape, the whole being held firmly together by screw H.

I do not wish to confine myself to the special construction of the plane herein described, as this may be variously modified without changing the principle of my invention; but

What I do claim as my invention, and desire to secure by Letters Patent, is—

The exposing of the cutting-edge of bit B always evenly and securely at one operation, as described, or any other way substantially the same.

S. MILLER.
